UNITED STATES PATENT OFFICE

CHARLES F. MILLER, OF COLUMBUS, OHIO

STOOL

Application filed April 30, 1929. Serial No. 359,243.

This invention relates to improvements in stools or similar objects of furniture, and has for its primary object to provide a stool of this character which is adapted for use upon street cars or other moving vehicles. The device may also be used as office or laboratory stools and may also find use in various other fields where a stool of great flexibility is required and which will adapt itself to the ever-changing position of the occupant. This object is accomplished by the provision of an improved spring structure which serves to absorb the shocks imparted thereto and to prevent jolts and jars from interfering with the comfort of the occupant, thus insuring complete relaxation of the occupant while in any position.

The present invention consists in the provision of a stool wherein is embodied a rigid frame structure, a seat, a stem depending from the seat and an improved spring structure including radially extending springs which are adapted to be connected with the frame and with upper and lower collars loosely mounted upon the stem and said radially extending springs being supplemented by vertically disposed springs which connect an intermediate collar and the upper end of said frame and serve to resiliently support the seat when the latter is occupied. The provision of the lower collar and the radially disposed springs is an improvement over my patent issued November 29, 1921, No. 1,398,938, and by means of the lowermost collar undue side movement on the lower end of the stem is prevented. It is to this feature that the present invention is particularly directed.

A further understanding of the invention is to be had by referring to the following description, and to the accompanying drawing, in which similar characters of reference denote like and corresponding parts. In said drawing:

Figure 1 is a side elevation of the spring stool comprising the present invention,

Figure 2 is a vertical longitudinal view taken through the stool,

Figure 3 is a horizontal sectional view taken on the plane indicated by the line 3—3 of Figure 1.

Referring more particularly to the details of the invention, the numeral 1 designates my improved stool in its entirety. The stool consists of a suitable frame which in this instance is formed from metallic channel members 2 vertically disposed and united by means of rigid cross-bars 3. The channel members and the cross-bars may be bent to any suitable shape and form to give the stool a pleasing appearance and by means of this construction the frame is rendered substantially capable of withstanding hard and severe usage and at the same time permits the stool to be relatively light in weight so that it may be readily moved from one place to another.

Centrally and vertically disposed within the frame structure is a stem 4 having a seat structure 5 mounted at its upper end, the latter being of any suitable construction and if desired may embody an adjustable back rest 6. The lower portion of the stem 4 is threaded for a suitable distance, as indicated at 7, for the reception of a similarly threaded spider or collar 8 in which the stem is adjustable for vertical movement. The spider or collar 8 is formed with radially projecting arms 9, which have their outer ends connected with the lower ends of downwardly and inwardly sloping coil springs 9', the upper or outer ends of said springs being secured in any suitable manner to the corner members of the frame 1. It will be understood that these springs may be of any suitable size and number and are so positioned within the frame as to act together for the purpose of receiving and absorbing weights imparted to the seat structure 5.

Also carried by the lowermost end of the stem 4 is a threaded collar 10 identical in shape to that of the collar 8 which has its radial arms 11 connected with radially projecting springs 12. The springs 12 have their outer ends connected to the lower cross-members. This construction serves to stabilize the lower end of the stem and to prevent undue side movements when the seat is occupied. Carried by the upper ends of the frame members 2 is a plurality of radially projecting springs 13 which are situated to

extend substantially parallel with the springs 12 of the lower collar 10. These springs 13 have their inner ends connected with the outer portions of radially extending arms 5 provided upon a collar 14. The latter is loosely positioned around the upper portion of the stem 4. This upper spring construction together with the collar 14 serves to centralize the stem 4 and to effect its resilient 10 support within the frame structure. It will be observed that the springs connecting the upper and the lower of said collars are anchored to the frame at a point substantially 45° apart. This preserves the equilibrium of 15 the stool and absorbs the shock imparted to the seat from every angle. The collar 14 is held in its proper position with respect to the stem 4 by means of a rebound or absorbent spring 15, surrounding the stem 4, and is 20 positioned between the collar 14 and the collar 8.

By reason of the location of the spring 15 it will be seen that an upward movement on the part of the seat is arrested, when weight 25 upon the latter is suddenly removed therefrom, and the operation of the stool is thus rendered automatic insuring the removal of jolts and shocks. It will be noted that by means of the lateral springs connected to the 30 upper and lower collars of the stem, lateral movement on the part of the seat is precluded and that the same is resilient only with respect to the vertical. By providing a threaded stem, adjustments in a vertical direction 35 may be imparted to the seat in order that the stool may be accommodated to the different heights required by different occupants. The lower end of the frame constituting the leg members for the stool may be equipped with 40 roller castors 16 if desired. In case the stool is used in an office, rubber buffers may be provided in place of the castors to prevent marring the floors and to insure quiet when the stool is moved.

45 From the foregoing description taken in connection with the accompanying drawing, it will be seen that there is provided an improved stool construction, wherein the mechanism is of such character as to insure comfort to the user and longevity of the stool.

What is claimed is:

1. A stool of the character described, comprising a supporting frame, a seat, a stem depending from said seat and arranged vertically and centrally of said frame, a collar loosely carried by the upper end of said stem, a second collar threadedly received by the lower end of said stem, a third collar threadedly carried by said stem intermediate of 55 said first named collars, vertically extending shock absorbing springs connecting the intermediate collar to the upper end of said frame, radially disposed springs connecting the upper and lower collars and said frame, the 60 lower of said last mentioned springs being 65 anchored to the frame at a position intermediate to that of said upper radial springs.

2. A stool of the character described, comprising a supporting frame, a seat, a stem depending from said seat and arranged vertically and centrally of said frame, a collar loosely carried by the upper end of said stem, a second collar threadedly received by the lower end of said stem, a third collar threadedly carried by said stem intermediate of said first named collars, a rebound spring surrounding said stem and exerting pressure upon said first named collars and said intermediate collar, vertically extending shock absorbing springs connecting said intermediate collar to the upper end of said frame, and a plurality of radially extending springs extending between the upper and the lower of said collars and said supporting frame.

In testimony whereof I affix my signature.

CHARLES F. MILLER.
